CLAIM

The ornamental design for a digital camera, as shown and described.

DESCRIPTION

FIG. 1 is a front-left perspective view of a digital camera showing my new design;

FIG. 2 is a rear-left perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof; and,

FIG. 9 is a rear-right perspective view thereof.

The broken lines shown in the drawings depict portions of the digital camera that form no part of the claimed design.

1 Claim, 8 Drawing Sheets
